(57) **CLAIM**

The ornamental design for a glasses holder, as shown and described.

DESCRIPTION

FIG. 1 is a front, right and top perspective view of a glasses holder, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The dotted broken lines and area enclosed by them in the FIG. 7 view illustrate portions of the glasses holder that form no part of the claimed design.

The dot-dash broken line boundary seen in FIGS. 3 and 6 defines the bounds of the claimed design and forms no part thereof.
